UNITED STATES PATENT OFFICE

2,506,758

SELF-CONTAINED AIR-CONDITIONING UNIT

Henry S. Woodruff, Cazenovia, N. Y., assignor to
Carrier Corporation, Syracuse, N. Y., a corpora-
tion of Delaware

Application February 27, 1947, Serial No. 731,363

1 Claim. (CL 62—129)

1

This invention relates to self-contained air conditioning units and more particularly to a self-contained air conditioning unit including means for supplying a minor portion of conditioned air to the refrigeration compartment to cool heat generating elements therein.

In self-contained air conditioning units, customary practice has been to cool heat generating elements in the refrigeration or machine compartment by the provision of finned heat exchange coils in the compartment; cooling water is circulated through said coils to cool the air in said compartment, raised in temperature by the heat generating members. While this system maintains the temperature in the machine or refrigeration compartment at a desired point, it considerably increases the initial cost of the unit due to the expense of the coils and to the plurality of connections which need be made.

The chief object of the present invention is to provide a self-contained air conditioning unit including economical means for cooling the refrigeration compartment.

An object is to provide a self-contained air conditioning unit containing a duct connecting the discharge end of the fan with the refrigeration compartment to permit a minor portion of cooled air to be supplied to the machine compartment in heat exchange relation with elements therein.

A further object is to provide a self-contained air conditioning unit including means for withdrawing a minor portion of cooled dehumidified air from the fan and for supplying such cooled dehumidified air to the refrigeration compartment. Other objects of my invention will be readily perceived from the following description.

This invention relates to a self-contained air conditioning unit which comprises in combination a heat exchange member for conditioning air, means for drawing air to be conditioned through said member and for discharging the conditioned air from the unit, a refrigeration compartment containing heat generating elements of the system, and a duct connecting the discharge end of said means and the compartment whereby a minor portion of conditioned air is supplied by said means to the compartment in heat exchange relation with elements therein.

The attached drawing illustrates a preferred embodiment of my invention, in which:

Figure 1 is a view partly in section and partly in elevation illustrating the self-contained air conditioning unit of my invention; and

Figure 2 is a plan view of the unit shown in

2

Figure 1, having the upper compartment removed.

Referring to the drawing, there is shown a self-contained air conditioning unit designated generally at 2. Preferably, unit 2 comprises a plurality of separate compartments 3, 4 and 5, each having top walls 6, side walls 7, and bases 8. Compartment 3 comprises the refrigeration or machine compartment of unit 2, and contains heat generating members of the refrigeration system, for example, the compressor 9 and the motor 10. Condenser 11 may be disposed in compartment 3 and may comprise a shell and coil structure, the refrigerant therein being cooled by cooling water passing through the coil. An opening 12 is provided in the top wall 6 of compartment 3 for a purpose hereinafter explained.

Compartment 4 contains the evaporator 13 of the system which may be supported in desired position by the walls thereof and which is connected to the condenser 11 and compressor 9 as is customary; filters 14 and a centrifugal fan 15 supported by the side walls 7 thereof are also disposed in compartment 4. A grille 16 is provided in the front wall 6 of compartment 4 to permit air from the area being conditioned to be drawn within the compartment through filters 14 and evaporator 13.

Cooled air is discharged by fan 15 into compartment 5. Compartment 5 contains a grille 17 to permit the cooled air to be distributed within the area being conditioned.

A duct 18 connects the discharge end of fan 15 with the opening 12 in the top wall 6 of compartment 3. Duct 18 includes a portion 19 extending into the stream of discharged air being supplied by fan 15 to compartment 5. Extended portion 19 in effect forms a scoop to direct a minor portion of the air within duct 18. Duct 18 extends in a horizontal direction adjacent the top wall 6 of compartment 4 and then in a vertical direction adjacent a side wall 7 of compartment 4 to the opening 12 in the top wall of compartment 3.

In operation of the unit, the motor 10 and compressor 9 generate heat. Fan 15 draws air from the area being conditioned through the filters 14 and evaporator 13 to filter and to cool the air. Fan 15 then supplies the filtered, cooled air to compartment 5 for distribution through grille 17 to the area being conditioned. Scoop 19 directs a minor portion of the filtered, cooled air into duct 18; the pressure created by fan 15 forces such air through duct 18 to compartment 3. In compartment 3 the cooled air passes over the

heat creating elements such as compressor 9 and motor 16 and serves to cool the same.

This invention provides an inexpensive and ready means whereby heat creating elements of the self-contained air conditioning unit may be protected against high temperatures due to prolonged use of the apparatus. The means so provided do not increase the cost of the unit to any substantial extent and satisfactorily maintain heat generating elements of the system at a temperature permitting operation for extended periods without injury thereto.

While I have described and illustrated a preferred embodiment of my invention, it will be understood my invention is not limited thereto since it may be otherwise embodied within the scope of the following claim.

I claim:

In a self-contained air conditioning unit, the combination of a first compartment having side 20 walls, a top wall and a base, an evaporator disposed within said compartment and supported by the walls thereof, a centrifugal fan disposed within said compartment and supported by the walls thereof, said fan serving to draw air to be 25 cooled through said evaporator and to discharge the cooled air into a second compartment for supply to an area being conditioned, a third compartment containing a condenser, a compressor, and a motor for actuating the compressor, the 30 condenser and the compressor in said third compartment being connected to the evaporator in

said first compartment cooling medium being supplied to said condenser in heat exchange relation with refrigerant therein, and a duct disposed in said first compartment connecting the discharge end of the fan with said third compartment, said duct having an extended portion extending within the path of the discharged stream of cooled air to direct cooled air within the duct, said duct extending in a horizontal direction adjacent the top wall of said first compartment and then extending in a vertical direction adjacent a side wall thereof to form a passage between the discharge end of said fan and the third compartment whereby a minor portion of conditioned air is supplied by the fan to said third compartment in heat exchange relation with the compressor and motor therein.

HENRY S. WOODRUFF.
